UNITED STATES PATENT OFFICE

151,192

DESIGN FOR A BOTTLE DRAINER

Harry Roe, Kansas City, Mo.

Application March 10, 1947, Serial No. 137,494

Term of patent 14 years

(Cl. D91—1)

To all whom it may concern:

Be it known that I, Harry Roe, a citizen of the United States, residing at Kansas City, in the county of Jackson and State of Missouri, have invented a new, original, and ornamental Design for a Bottle Drainer, of which the following is a specification, reference being had to the accompanying drawing, forming a part thereof.

Figure 1 is a front elevation of the bottle drainer, showing my new design.

Fig. 2 is an end elevation of the bottle drainer.

Fig. 3 is a top plan view of the bottle drainer; and

Fig. 4 is a rear elevation thereof.

I claim:

The ornamental design for a bottle drainer, as shown.

HARRY ROE.
